MEANS FOR DRAWING-OFF SLIVERS IN
COMBING AND LIKE MACHINES USED IN
THE PREPARATION OF TEXTILE FIBERS
FOR SPINNINGPercy Joseph Gillespie, Golders Green,
London, EnglandApplication June 10, 1935, Serial No. 25,910
In Great Britain June 1, 1934

2 Claims. (Cl. 19—115)

This invention provides improved means for drawing-off slivers and for like operations in combing and like machines used in preparing textile fibres for spinning.

5 In wide combing machines, such as the French combing machines, the means commonly used for effecting a drawing-off operation comprise a pair of fusiform rollers, one a driver and the other an idler, of small maximum diameter relative to 10 their length and set close to a comb, with a wide, endless drawing-off band of leather running about the driving roller and at least one spaced guide roller.

A disadvantage of the known means is that 15 the band in passing about the fusiform driving roller is slack at its edges even when drawn tight at its middle. Consequently, when the belt passes between the driving and idling rollers adjacent the comb, the action of the machine causes the bands at the low edges of the driving roller to "belly" and flap forward between the rollers and the comb, and frequently catch upon the teeth of the latter and suffer small hacks or tears. These catch the fibres being combed, which eventually 20 form slubs liable to become entangled in the combed slivers with resultant disadvantage in the subsequent spinning and weaving processes. Furthermore, in some combing machines, upper and lower blades known as "swords" reciprocate upwards and downwards between the 25 comb and the rollers, nearly touching the band, and these blades also tend to catch and rupture any loose part of the band, particularly at the edges thereof. Cutting out of the hacked or torn edge portions of the band has been practised 30 hitherto for preventing slubs gathered by such portions from being drawn into the combed slivers. Moreover, the ruptures in the band are liable to extend rapidly and consequently materially 35 shorten the life of the band.

40 My present invention has for an object to overcome the aforesaid disadvantages.

Accordingly, I provide, in combination with a 45 fusiform driving roller of drawing-off means in a wide combing machine, a band of leather, rubber or other material which is bellied in manufacture from its edges to its middle in conformity with the varying diameters of the driving roller.

50 Thus, under my invention drawing-off means in a wide combing machine comprises, in combination, a pair of driving and idler rollers and a band of leather, rubber or other material, the driving roller and the band being relatively so formed that the edges of the band are main-

tained in close contact with the driving roller when passing round it.

The surfaces of the rollers, whether fusiform or cylindrical, may in known manner be fluted or scratch-fluted longitudinally or helically, or otherwise roughened, or may be smooth.

The band in drawing-off means according to the invention may be endlessly moulded or otherwise made, for example, of rubber, with or without reinforcement.

10 I may carry out my invention, for example, without structural modification of an existing machine by retaining the usual fusiform driving roller for the drawing-off band, and substituting for the usual cylindrical band a band bellied in 15 manufacture from its edges to its middle in conformity with the shape of the driving roller. The peripheral length of the band decreases progressively from its middle to its edges, the amount of the decrease at any plane being substantially 20 equal to the difference between the circumference of the driving roller at that plane and the circumference of the roller at its middle plane. That is to say, the peripheral length of the band in any plane is varied substantially according to 25 the formula

$$l_e = l_m - \pi(d_m - d_e)$$

30 where l_e and l_m are the lengths of the band in the plane in question and the middle plane respectively, and d_e and d_m are the diameters of the roller in the same planes. In practice, it has been ascertained that a band having a peripheral length of 23" at its middle and 22½" at its 35 edges operates satisfactorily in conjunction with a driving roller having a maximum diameter at its middle of 1", decreasing to 7/8" at its ends.

Fig. 1 is a perspective view of part of an existing combing machine to which the invention is applied without structural modification (the curvature of the rollers being greatly exaggerated for clarity). The usual fusiform driving roller a is retained, and for the usual cylindrical band there is substituted a band b bellied from its edges to its middle in conformity with the shape of the driving roller. The jockey roller c is also fusiform in correspondence with the shape of the band b , while the usual fusiform idler roller is retained so that when the rollers a and d are strained under the pressure of the springs on 45 their bearings they ensure a sufficient and equal pull over the whole width of the band on the fibers drawn from the comb e . The upper sword f is shown in its lowermost position between the roller a and the comb e and the figure indicates 50 55

how little clearance there is at the ends of the roller *a*, so that the least flapping of the edges of the band (which is eliminated by the invention) renders them liable to be cut and hacked 5 by the swords.

Fig. 2 is a cross section of the band *b* and shows how it clings to the roller *a* at its edges on account of its special formation.

In a combing machine for preparing textile 10 fibers for spinning, having drawing-off means according to the foregoing example, the possibility of the band being hacked or torn by flapping or running loosely at its edges and consequently being caught by parts of a machine 15 is advantageously removed, thereby obviating the necessity for cutting out hacked or torn edge portions of the bands, and securing material lengthening of the useful life of the bands.

I claim:—

1. Means for drawing off slivers and for like operations in a wide combing machine, comprising, in combination, a fusiform driving roller, a co-operating idler roller, and a flexible band passing about said driving roller and between 5 said driving and idler rollers, said band being bellied in manufacture from its edges to its middle in conformity with the varying diameters of the driving roller.

2. Means for drawing off slivers and for like 10 operations in a wide combing machine, comprising, in combination, a fusiform driving roller, a co-operating idler roller, and an endlessly moulded rubber band passing about said driving roller and between said driving and idler rollers, said 15 band being bellied in manufacture from its edges to its middle in conformity with the varying diameters of the driving roller.

PERCY JOSEPH GILLESPIE.
